Jeremiah Joseph Sullivan

UNITED STATES PATENT OFFICE.

JEREMIAH JOSEPH SULLIVAN, OF LOUISVILLE, KENTUCKY.

BRAKE-APPLICATION VALVE FOR TRAIN-PIPES.

SPECIFICATION forming part of Letters Patent No. 656,058, dated August 14, 1900.

Application filed March 2, 1900. Serial No. 7,057. (No model.)

To all whom it may concern:

Be it known that I, JEREMIAH JOSEPH SULLIVAN, a citizen of the United States, residing at Louisville, in the county of Jefferson and State of Kentucky, have invented a certain new and useful device adapted to be used on freight-cars equipped with air-brakes and on passenger-cars in case of inoperative train-pipes, of which the following is a full, clear, and exact description, reference being had to the accompanying drawings, forming part of this specification.

My invention relates to a coupling-head for trains having an air-passage leading to the atmosphere outside, there being valve mechanism normally sealing the passage and exteriorly-fulcrumed lever mechanism connected to the valve, whereby with proper operative connecting means for tripping the lever the air may be escaped from the head by the operator at any point along the length of the train, thereby applying the brakes.

In the drawings, Figure 1 is a plan view, Fig. 2 is a side elevation, Fig. 3 an end elevation, and Fig. 4 a transverse section, showing the valve as arranged for releasing the air from the train-pipe.

The casing or intermediate connection A has the lugs B and C, designed to be interchangeable with the hose-couplings at present in use between cars for the purpose of making a continuous line of piping from end to end of the train, this arrangement being commonly known as the "train-pipe," which is now almost universally in use and so well known that further description here is not considered necessary, the rubber gaskets D coinciding with similar gaskets in the couplings and forming a joint capable of retaining the air and one that is easily and quickly made. A port or passage E to the valve-chamber F permits the air contained in the train-pipe to be released by the valve G, a cord or wire being attached to the bell-crank lever H and secured at or near the running-board, ladder, or other suitable location enabling the person in charge to apply the brakes and control the train, the spring I, placed at the end of the valve-stem, seating the valve when the air is released. It is evident that such devices can be placed at several locations in a train-pipe before start-

ing, and any difficulty arising the trainmen can quickly stop the train.

Instances have occurred when engineers have forgotten orders and passed points where they should have stopped until trains have passed, causing serious collisions, and as these meeting-points are usually arranged to not delay the train more than absolutely necessary a failure to stop at the designated point requires immediate action on the part of the trainmen, the engineer often observing the signals given too late to have the line clear for the approaching train.

I do not know of a similar device in use at this time, and as several equivalent mechanisms can be arranged I do not wish to be limited to the design shown. A wrought-iron pipe or rubber hose can be attached to the intermediate connection operated by suitable mechanism at the top of the car and enabling in the application of the brakes.

Having thus described my invention, what I claim, and desire to secure by Letters Patent, is—

1. In combination with a coupling-head, having an air-compartment, means for connecting the two adjoining ends of a hose-pipe thereto, an air-passage connecting the air-compartment of said head with the external atmosphere, valve mechanism seated in said passage normally sealing the same, and an exteriorly-fulcrumed lever connected thereto for tripping said valve, substantially as specified.

2. In a coupling-head having an air-compartment, the combination of means for connecting the adjoining ends of a hose-pipe thereto, a valve-chamber connected to said head, an air connecting-passage between said compartment and chamber, an air-escape passage tapping said chamber, valve mechanism seated in said chamber normally sealing one of said passages, and an exteriorly-fulcrumed lever engaging the valve-stem and adapted to trip the same, substantially as specified.

3. In a coupling-head having an air-compartment, the combination of means for coupling the adjoining ends of a hose-pipe thereto, a valve-chamber connected to said head parallel with the barrel thereof, a passage between said compartment and chamber, an air-escape passage in the end of said chamber, a

valve seated in said chamber normally sealing one of said passages, and an exteriorly-fulcrumed lever engaging the valve-stem which is tripped to connect said passages, 5 substantially as specified.

4. In combination with a coupling-head having an air-compartment, means for connecting thereto the adjoining ends of a train hose-pipe, a valve-chamber connected to said 10 head, an air-passage between said air compartment and chamber, a valve seated in said

chamber, an air-escape orifice tapping said valve, a tripping-lever pivoted to the valve-chamber, the inner end of said lever engaging the valve-stem, and the outer end of said 15 lever being free to move, substantially as specified.

JEREMIAH JOSEPH SULLIVAN.
